UNITED STATES PATENT OFFICE

JULIUS MOHR, OF MILWAUKEE, WISCONSIN

TOY VEHICLE

Application filed March 8, 1928. Serial No. 260,227.

This invention relates to toy vehicles.

Objects of this invention are to provide a toy vehicle such as a sled which is so constructed that the device may be readily steered by the occupant by means of a handle, and in which provision is made for adjusting the angular setting of the handle while retaining its secure, operative connection with the front runner or guiding member.

5 A further object of this invention is to provide a novel form of sled which is so constructed that it can be used for a small sized sled adapted for one person, or which may be readily elongated by folding down an additional board so as to provide for the seating of several other riders.

10 Further objects are to provide a sled which is adapted to receive a removable tool at its front end, such as a scraper or brush, for instance, whereby the soft snow will be plowed or brushed to the side to provide a clear passageway for the sled.

15 Further objects are to provide novel means for adjusting the front tool or scraper, so that it may be set at any desired angle or may be completely removed.

20 Further objects are to provide means for adjustably locking the steering member at the front, for example, the front runner, so as not to require any steering on the part of the operator.

25 An embodiment of the invention is shown in the accompanying drawings in which:

Figure 1 is a side view of the device with 30 parts in section;

Figure 2 is a plan view with the upper portion of the steering apparatus sectioned off.

35 Referring to the drawings, it will be seen that the sled comprises a body portion or board 1 which is equipped with rear runners 2, and a steering front runner 3. This front runner is rigidly connected by means of a shaft 4 to a sector-shaped plate 5. The plate 5 pivotally carries the forked lower end of the 40 steering arm 6, such steering arm being provided with an upper handle 7. This steering arm is adapted to be rocked into any desired position and is apertured. The sector 5 is also apertured, as indicated by the reference 45 character 8, and the steering arm is adapted

55 to be locked in any desired adjusted position by means of the pin 9. The steering arm is provided with an additional aperture 10 for the reception of the pin when it is not in use.

60 The front spindle 4 passes through a metal bushing 11 and a forwardly projecting arm 12 is integrally formed with the bushing 11. This arm 12 carries a head 13 which is set within the forward outline of the rounded end 1' of the body 1, as may be seen from reference to Figure 2. This arm 12 and the body portion 1 are provided with an aperture 14 which is adapted to align with an aperture 15 formed in the front runner, so that if desired a pin may be slipped through these apertures to the front runner in its straight-ahead position.

65 The sled is adapted to removably carry a tool 16 which may be a scraper, a brush, or other device, and this tool is provided with a pair of arms 17 which fit over the top and bottom of the head 13. It is pivotally and removably joined to the head by means of the bolt 18. This tool is provided with eyelets 19 (see Figure 2) adjacent its ends which may receive cords, so that the occupant of the sled may adjust the angular setting of the tool. Also, the tool is provided with rearwardly projecting arms 20 which are equipped with apertures 21. These apertures are adapted to align with apertures 22 when the tool is rocked into an angular position, as shown in Figure 2. When in this position, a pin is passed through the aligning apertures 21 and 22 to thus hold the tool in its angular, adjusted position.

70 The sled is provided with a seat 23 which is carried by a forward upright 24 and a rear upright 25. Between these uprights, a plate or bottom 26 is positioned to secure additional rigidity. If desired, this seat may be formed with side and back portions, as indicated in dotted lines in Figure 1. The rear support 25 for the seat is apertured and a 75 spring 27 passes through the aperture. This spring is provided with a clip or shouldered portion which passes through an aperture 28 formed in a hinged board 29, so as to retain the hinged board 29 in its upright position 80

85 10

and to permit its ready lowering when the spring or latch 27 is raised.

The board 29 is really an extension of the body portion and is hinged to the body portion, as indicated at 30. It is provided with a runner 31. When it is desired to use the sled for a single person, the parts are in their full line position, as shown in Figure 1. When, however, additional seating capacity is desired, the latch or spring 27 is released and the extension member 29 is allowed to rock downwardly into the dotted line position to thus accommodate additional passengers.

It will be seen, therefore, that a very simple type of toy vehicle has been provided which is easy to construct, which is of novel formation, which is adjustable to accommodate one or more riders, and which is equipped with novel steering means and means for receiving a tool at its forward end.

Although the invention has been described in considerable detail, such description is intended as illustrative rather than limiting as the invention may be variously embodied and as the scope of such invention is to be determined as claimed.

I claim:

A sled comprising a body portion having runners, a seat carried by the body portion, an extension board hinged to the body portion rearwardly of said seat, latching means carried by said seat for temporarily retaining said extension board in upright position, said extension board being adapted to rock downwardly and to project rearwardly behind said seat, said extension board being provided with a runner.

In testimony that I claim the foregoing I have hereunto set my hand at Milwaukee, in the county of Milwaukee and State of Wisconsin.

JULIUS MOHR.
